US00D536090S

(12) **United States Design Patent** (10) Patent No.: **US D536,090 S**
(45) Date of Patent: **** Jan. 30, 2007**

(54) **HAND HELD CORDLESS HOT GAS VOLATIZING DEVICE**

(75) Inventor: **Stephen G. Nelson**, San Diego, CA (US)

(73) Assignee: **Zhao Wei LLC**, San Diego, CA (US)

(**) Term: **14 Years**

(21) Appl. No.: **29/217,574**

(22) Filed: **Nov. 18, 2004**

(51) LOC (8) Cl. **29-02**

(52) U.S. Cl. **D24/110**

(58) Field of Classification Search **D24/110; 128/203.15, 200.14, 200.23, 200.21, 203.12**
See application file for complete search history.
